US011541517B2

(12) United States Patent
Hsieh

(10) Patent No.: US 11,541,517 B2
(45) Date of Patent: Jan. 3, 2023

(54) THREE-PIECE WRENCH(71) Applicant: KABO TOOL COMPANY, Taichung (TW)(72) Inventor: Chih-Ching Hsieh, Taichung (TW)(73) Assignee: KABO TOOL COMPANY, Taichung (TW)

(*) Notice: Subject to any disclaimer, the term of this patent is extended or adjusted under 35 U.S.C. 154(b) by 349 days.

(21) Appl. No.: 16/868,305(22) Filed: May 6, 2020(65) Prior Publication Data

US 2020/0398408 A1 Dec. 24, 2020

(30) Foreign Application Priority Data

Jun. 19, 2019 (TW) 108121365

(51) Int. Cl.

B25B 23/00 (2006.01)
B25B 13/10 (2006.01)
B25B 13/46 (2006.01)
B25B 23/16 (2006.01)
B25G 1/04 (2006.01)
B25G 3/10 (2006.01)

(52) U.S. Cl.

CPC B25B 23/0021 (2013.01); B25B 13/107 (2013.01); B25B 13/46 (2013.01); B25B 23/16 (2013.01); B25G 1/043 (2013.01); B25G 3/10 (2013.01)

(58) Field of Classification Search

CPC . B25G 1/043; B25G 1/04; B25G 4/10; B25G 3/10; B25B 23/0021; B25B 23/16; B25B 13/107; B25B 13/46

See application file for complete search history.

(56)

References Cited

U.S. PATENT DOCUMENTS

6,336,382 B2 *	1/2002	Cerda	B25B 13/461
			81/177.85
6,883,402 B2 *	4/2005	Cerda	B25B 13/461
			81/177.85
7,024,969 B2 *	4/2006	Smith	B25B 13/08
			81/177.2
7,044,028 B1 *	5/2006	Lozano	B25B 23/0021
			81/177.85
8,141,462 B2 *	3/2012	Richardson	B25B 13/04
			81/177.2
8,312,795 B2 *	11/2012	Richardson	B25B 23/0028
			81/177.8
11,027,409 B2 *	6/2021	Macor	B25B 23/0007
2006/0016297 A1 *	1/2006	Smith	B25B 13/04
			81/177.2
2009/0013834 A1 *	1/2009	Richardson	B25G 1/043
			81/177.8

(Continued)

Primary Examiner — David B. Thomas(74) Attorney, Agent, or Firm — Guice Patents PLLC

(57)

ABSTRACT

The present invention relates to a three-piece wrench comprising: a wrench body with a working head and a shaft, the working head is located at a front end of the shaft, the shaft has a length; a first extension rod with a length; and a second extension rod with a length; the lengths of the first extension rod and the second extension rod are greater than the length of the shaft; combination of the wrench body, the first extension rod and the second extension rod provides various usage lengths of the wrench, so that different connection types can be used to form required lengths according to requirements.

7 Claims, 8 Drawing Sheets(56)

References Cited

U.S. PATENT DOCUMENTS

- 2010/0107828 A1* 5/2010 Huerta B25G 1/063
81/177.85
2014/0260829 A1* 9/2014 Alfinito B25B 23/0021
81/177.85
2021/0031354 A1* 2/2021 Harr B25B 13/462

* cited by examiner

Fig. 1
PRIOR ART

Fig. 2

Fig. 4

Fig. 3

Fig. 7

Fig. 8

Fig. 9

Fig. 10

1

THREE-PIECE WRENCH

BACKGROUND OF THE INVENTION

Field of Invention

The present invention relates to a tool, and more particularly to a three-piece wrench with various length variations.

Related Art

Generally, hand-held tools are provided with different lengths of grips in different usage states to be used for different requirements of driving force. Please refer to FIG. 1 for four conventional wrenches with four different lengths, when small torsion is required or in narrow operation area, a wrench 91 with a shortest length is used; for general use or general torsion requirements, a wrench 92 or 93 with a medium length is used; and if larger torsion operation is required, such as heavy machinery or large objects, a wrench 94 with a longest length is used, and a larger moment of force will be generated through a longer arm of force to facilitate users to apply a larger torsion value.

In the current technology, in order to cope with different occasions of usage and operating torsions, operators have to purchase the wrenches 91, 92, 93, 94 of different lengths for usage, in addition to the high costs of purchase, the different lengths will make it difficult to store away and larger storage space is required, and the four wrenches are heavy and inconvenient to carry.

SUMMARY OF THE INVENTION

An object of the present invention is to provide a three-piece wrench, so that a single wrench is capable of producing different length variations according to different requirements of usage.

Another object of the present invention is to provide a three-piece wrench capable of improving the convenience of use, reducing the purchase costs and facilitating portability.

A three-piece wrench provided by the present invention includes:

a wrench body having a shaft and a working head, the working head is located at a front end of the shaft, the shaft has a length;

a first extension rod with a length;

a second extension rod with a length;

two rear combination portions respectively provided at rear ends of the shaft and the first extension rod; and two front combination portions respectively provided at front ends of the first extension rod and the second extension rod, each of the front combination portions and each of the rear combination portions are detachably combined;

the lengths of the first extension rod and the second extension rod are greater than the length of the shaft; and the wrench body, the first extension rod and the second extension rod provide various lengths of usage for the wrench.

Thereby, the wrench body is capable of producing different length variations through variations in connection with or without the first extension rod and the second extension rod; when the wrench body is changed in length, changes can be done without the working head leaving a workpiece to increase the efficiency of changing length, and the first extension rod and the second extension rod can be directly combined with the wrench body when not in use, which can be conveniently stored away without occupying space.

2

Preferably, the length of the second extension rod is greater than the length of the first extension rod.

Preferably, the working head is integrally formed with the shaft.

BRIEF DESCRIPTION OF THE DRAWINGS

The objects, features and efficacies of the present invention can be understood from the description of the following 10 preferred embodiments:

FIG. 1 is a perspective view of conventional wrenches with different lengths;

FIG. 2 is an exploded perspective view of a three-piece wrench of a first preferred embodiment of the present 15 invention;

FIG. 3 is a cross-sectional view of a connection position of the first preferred embodiment of the present invention;

FIG. 4 is a perspective view of a wrench body of the first 20 preferred embodiment of the present invention;

FIG. 5 is a perspective view of connection between the wrench body and a first extension rod of the first preferred embodiment of the present invention;

FIG. 6 is a perspective view of connection between the wrench body and a second extension rod of the first preferred 25 embodiment of the present invention;

FIG. 7 is a perspective view of connections between the wrench body and the first extension rod and the second extension rod of the first preferred embodiment of the present invention;

FIG. 8 is a perspective view of the wrench body of a 30 second preferred embodiment of the present invention;

FIG. 9 is an exploded perspective view of the three-piece wrench of a third preferred embodiment of the present invention; and

FIG. 10 is an exploded perspective view of the three-piece 35 wrench of a fourth preferred embodiment of the present invention.

DETAILED DESCRIPTION OF THE INVENTION

Please refer to FIG. 2 to FIG. 4 for a three-piece wrench 10 provided by a first preferred embodiment of the present invention, the three-piece wrench 10 mainly includes a 40 wrench body 20, a first extension rod 30, and a second extension rod 40.

The wrench body 20 has a working head 21 and a shaft 22, the shaft 22 has a length L1, the working head 21 is located at a front end of the wrench body 20, and the working head 21 in this preferred embodiment is a ratchet head with a ratchet structure inside. The working head 21 can be of other forms, such as a working head with a polygonal fitting hole, which is not limited to what is shown in this preferred embodiment. The shaft 22 is located at a rear end of the wrench body 20 and is provided with a rear combination portion 23 at a rear end of the shaft 22. The rear combination portion 23 is an insertion slot 231 formed as a cylindrical slot to be recessed at the rear end of the shaft 22, and a peripheral wall of the insertion slot 231 is penetratively disposed with a positioning hole 232.

The first extension rod 30 has a length L2, the length L2 is greater than the length L1 of the shaft 22. The first extension rod 30 is provided with a front combination portion 31 at a front end, and a rear combination portion 32 at a rear end with structure and dimensions the same as that of the rear combination portion 23 of the wrench body 20. The front combination portion 31 is a plug 311, which is a cylinder, and an accommodating hole 312 is provided on a peripheral surface of the plug 311 in a radial direction. An elastic positioning member 33 is disposed on the front combination portion 31 and in the accommodating hole 312, the elastic positioning member 33 is composed of a ball 331 and an elastic element 332. The front combination portion 31 can be combined with the rear combination portion 23 of the wrench body 20 so that the plug 311 can be inserted into the insertion slot 231. After the plug 311 is inserted into the insertion slot 231, the elastic element 332 of the elastic positioning member 33 will make the ball 331 to produce an elastic force, and the ball 331 can be elastically snapped in the positioning hole 232, so that the first extension rod 30 is capable of detachably inserting into the rear end of the wrench body 20. The rear combination portion 32 is provided with an insertion slot 321 at a rear end of the first extension rod 30, the insertion slot 321 is formed as a cylindrical hole of a same size as the insertion slot 231, and a peripheral wall of the insertion slot 321 is penetratively disposed with a positioning hole 322.

60 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130 131 132 133 134 135 136 137 138 139 140 141 142 143 144 145 146 147 148 149 150 151 152 153 154 155 156 157 158 159 160 161 162 163 164 165 166 167 168 169 170 171 172 173 174 175 176 177 178 179 180 181 182 183 184 185 186 187 188 189 190 191 192 193 194 195 196 197 198 199 200 201 202 203 204 205 206 207 208 209 210 211 212 213 214 215 216 217 218 219 220 221 222 223 224 225 226 227 228 229 230 231 232 233 234 235 236 237 238 239 240 241 242 243 244 245 246 247 248 249 250 251 252 253 254 255 256 257 258 259 2510 2511 2512 2513 2514 2515 2516 2517 2518 2519 2520 2521 2522 2523 2524 2525 2526 2527 2528 2529 2530 2531 2532 2533 2534 2535 2536 2537 2538 2539 2540 2541 2542 2543 2544 2545 2546 2547 2548 2549 2550 2551 2552 2553 2554 2555 2556 2557 2558 2559 25510 25511 25512 25513 25514 25515 25516 25517 25518 25519 25520 25521 25522 25523 25524 25525 25526 25527 25528 25529 25530 25531 25532 25533 25534 25535 25536 25537 25538 25539 25540 25541 25542 25543 25544 25545 25546 25547 25548 25549 255410 255411 255412 255413 255414 255415 255416 255417 255418 255419 255420 255421 255422 255423 255424 255425 255426 255427 255428 255429 255430 255431 255432 255433 255434 255435 255436 255437 255438 255439 255440 255441 255442 255443 255444 255445 255446 255447 255448 255449 255450 255451 255452 255453 255454 255455 255456 255457 255458 255459 255460 255461 255462 255463 255464 255465 255466 255467 255468 255469 255470 255471 255472 255473 255474 255475 255476 255477 255478 255479 255480 255481 255482 255483 255484 255485 255486 255487 255488 255489 255490 255491 255492 255493 255494 255495 255496 255497 255498 255499 2554100 2554101 2554102 2554103 2554104 2554105 2554106 2554107 2554108 2554109 2554110 2554111 2554112 2554113 2554114 2554115 2554116 2554117 2554118 2554119 25541100 25541101 25541102 25541103 25541104 25541105 25541106 25541107 25541108 25541109 255411010 255411011 255411012 255411013 255411014 255411015 255411016 255411017 255411018 255411019 255411020 255411021 255411022 255411023 255411024 255411025 255411026 255411027 255411028 255411029 255411030 255411031 255411032 255411033 255411034 255411035 255411036 255411037 255411038 255411039 255411040 255411041 255411042 255411043 255411044 255411045 255411046 255411047 255411048 255411049 255411050 255411051 255411052 255411053 255411054 255411055 255411056 255411057 255411058 255411059 255411060 255411061 255411062 255411063 255411064 255411065 255411066 255411067 255411068 255411069 255411070 255411071 255411072 255411073 255411074 255411075 255411076 255411077 255411078 255411079 255411080 255411081 255411082 255411083 255411084 255411085 255411086 255411087 255411088 255411089 255411090 255411091 255411092 255411093 255411094 255411095 255411096 255411097 255411098 255411099 2554110100 2554110101 2554110102 2554110103 2554110104 2554110105 2554110106 2554110107 2554110108 2554110109 2554110110 2554110111 2554110112 2554110113 2554110114 2554110115 2554110116 2554110117 2554110118 2554110119 25541101100 25541101101 25541101102 25541101103 25541101104 25541101105 25541101106 25541101107 25541101108 25541101109 25541101110 25541101111 25541101112 25541101113 25541101114 25541101115 25541101116 25541101117 25541101118 25541101119 255411011100 255411011101 255411011102 255411011103 255411011104 255411011105 255411011106 255411011107 255411011108 255411011109 255411011110 255411011111 255411011112 255411011113 255411011114 255411011115 255411011116 255411011117 255411011118 255411011119 2554110111100 2554110111101 2554110111102 2554110111103 2554110111104 2554110111105 2554110111106 2554110111107 2554110111108 2554110111109 2554110111110 2554110111111 2554110111112 2554110111113 2554110111114 2554110111115 2554110111116 2554110111117 2554110111118 2554110111119 25541101111100 25541101111101 25541101111102 25541101111103 25541101111104 25541101111105 25541101111106 25541101111107 25541101111108 25541101111109 25541101111110 25541101111111 25541101111112 25541101111113 25541101111114 25541101111115 25541101111116 25541101111117 25541101111118 25541101111119 255411011111100 255411011111101 255411011111102 255411011111103 255411011111104 255411011111105 255411011111106 255411011111107 255411011111108 255411011111109 255411011111110 255411011111111 255411011111112 255411011111113 255411011111114 255411011111115 255411011111116 255411011111117 255411011111118 255411011111119 2554110111111100 2554110111111101 2554110111111102 2554110111111103 2554110111111104 2554110111111105 2554110111111106 2554110111111107 2554110111111108 2554110111111109 2554110111111110 2554110111111111 2554110111111112 2554110111111113 2554110111111114 2554110111111115 2554110111111116 2554110111111117 2554110111111118 2554110111111119 25541101111111100 25541101111111101 25541101111111102 25541101111111103 25541101111111104 25541101111111105 25541101111111106 25541101111111107 25541101111111108 25541101111111109 25541101111111110 25541101111111111 25541101111111112 25541101111111113 25541101111111114 25541101111111115 25541101111111116 25541101111111117 25541101111111118 25541101111111119 255411011111111100 255411011111111101 255411011111111102 255411011111111103 255411011111111104 255411011111111105 255411011111111106 255411011111111107 255411011111111108 255411011111111109 255411011111111110 255411011111111111 255411011111111112 255411011111111113 255411011111111114 255411011111111115 255411011111111116 255411011111111117 255411011111111118 255411011111111119 2554110111111111100 2554110111111111101 2554110111111111102 2554110111111111103 2554110111111111104 2554110111111111105 2554110111111111106 2554110111111111107 2554110111111111108 2554110111111111109 2554110111111111110 2554110111111111111 2554110111111111112 2554110111111111113 2554110111111111114 2554110111111111115 2554110111111111116 2554110111111111117 2554110111111111118 2554110111111111119 25541101111111111100 25541101111111111101 25541101111111111102 25541101111111111103 25541101111111111104 25541101111111111105 25541101111111111106 25541101111111111107 25541101111111111108 25541101111111111109 25541101111111111110 25541101111111111111 25541101111111111112 25541101111111111113 25541101111111111114 25541101111111111115 25541101111111111116 25541101111111111117 25541101111111111118 25541101111111111119 255411011111111111100 255411011111111111101 255411011111111111102 255411011111111111103 255411011111111111104 255411011111111111105 255411011111111111106 255411011111111111107 255411011111111111108 255411011111111111109 255411011111111111110 255411011111111111111 255411011111111111112 255411011111111111113 255411011111111111114 255411011111111111115 255411011111111111116 255411011111111111117 255411011111111111118 255411011111111111119 2554110111111111111100 2554110111111111111101 2554110111111111111102 2554110111111111111103 2554110111111111111104 2554110111111111111105 2554110111111111111106 2554110111111111111107 2554110111111111111108 2554110111111111111109 2554110111111111111110 2554110111111111111111 2554110111111111111112 2554110111111111111113 2554110111111111111114 2554110111111111111115 2554110111111111111116 2554110111111111111117 2554110111111111111118 2554110111111111111119 25541101111111111111100 25541101111111111111101 25541101111111111111102 25541101111111111111103 25541101111111111111104 25541101111111111111105 25541101111111111111106 25541101111111111111107 25541101111111111111108 25541101111111111111109 25541101111111111111110 25541101111111111111111 25541101111111111111112 25541101111111111111113 25541101111111111111114 25541101111111111111115 25541101111111111111116 25541101111111111111117 25541101111111111111118 25541101111111111111119 255411011111111111111100 255411011111111111111101 255411011111111111111102 255411011111111111111103 255411011111111111111104 255411011111111111111105 255411011111111111111106 255411011111111111111107 255411011111111111111108 255411011111111111111109 255411011111111111111110 255411011111111111111111 255411011111111111111112 255411011111111111111113 255411011111111111111114 255411011111111111111115 255411011111111111111116 255411011111111111111117 255411011111111111111118 255411011111111111111119 2554110111111111111111100 2554110111111111111111101 2554110111111111111111102 2554110111111111111111103 2554110111111111111111104 2554110111111111111111105 2554110111111111111111106 2554110111111111111111107 2554110111111111111111108 2554110111111111111111109 2554110111111111111111110 2554110111111111111111111 255411

The second extension rod 40 has a length L3 that is greater than the length L1 of the shaft 22 of the wrench body 20 and the length L2 of the first extension rod 30. The second extension rod 40 is provided with a front combination portion 41 at a front end with structure and dimensions the same as that of the front combination portion 31 of the first extension rod 30. The front combination portion 41 is a plug 411, formed as a cylinder of a same size as the plug 311, and an accommodating hole 412 is provided on a peripheral surface of the plug 411 in a radial direction. An elastic positioning member 42 is disposed on the front combination portion 41 and in the accommodating hole 412, the elastic positioning member 42 is composed of a ball 421 and an elastic element 422. The front combination portion 41 can be combined with the rear combination portion 23 of the wrench body 20 or the rear combination portion 32 of the first extension rod 30, so that the plug 411 can be inserted into the insertion slot 231 or the insertion slot 321. After the plug 411 is inserted into the insertion slot 231 or the insertion slot 321, the elastic element 422 of the elastic positioning member 42 will make the ball 421 to produce an elastic force, and the ball 421 can be elastically snapped in the positioning hole 232 or the positioning hole 322, so that the second extension rod 40 is capable of detachably inserting into the rear end of the wrench body 20 or the rear end of the first extension rod 30.

It can be known from the above description that the shaft 22 of the wrench body 20, the first extension rod 30 and the second extension rod 40 form three lengths, among which: the length L3 of the second extension rod 40 is the longest, the length L2 of the first extension rod 30 is the second longest, and the length L1 of the shaft 22 of the wrench body 20 is the shortest.

Please refer to FIG. 4, which shows one of the usage states of the three-piece wrench 10. The wrench body 20 can be used directly, users can directly hold on to a position of the shaft 22 of the wrench body 20 to rotate, and since the length L1 of the shaft 22 is short, it is suitable for use in small driving force and narrow space to facilitate operation.

Please refer to FIG. 5, which shows a second usage state of the three-piece wrench 10. When a torsion of the wrench 10 needs to be increased, the front combination portion 31 of the first extension rod 30 can be inserted into the rear combination portion 23 of the wrench body 20, so that the plug 311 of the front combination portion 31 can be inserted into the insertion slot 231 of the rear combination portion 23, and the ball 331 of the elastic positioning member 33 is elastically snapped and limited in the positioning hole 232, and the front combination portion 31 can be fixed in the rear combination portion 23. After the first extension rod 30 is combined with the wrench body 20, a length of the wrench 10 (not including a length of the working head 21, the same hereinafter) becomes the length L1 of the shaft 22 of the wrench body 20 combined with the length L2 of the first extension rod 30. In this way, the wrench 10 forms a second length (L1+L2), which can provide a second operating arm of force and greater torsion.

In addition, as shown in FIG. 3, when the first extension rod 30 is to be removed from the rear end of the wrench body 20, firstly press the ball 331 of the elastic positioning member 33, so that the ball 331 can sink into the accommodating hole 312, the ball 331 no longer limits the positioning hole 232, and the plug 311 can be removed from the insertion slot 231.

Furthermore, please refer to FIG. 6, which shows a third usage state of the three-piece wrench 10. The front combination portion 41 of the second extension rod 40 is combined with the rear combination portion 23 of the wrench body 20. Since the front combination portion 41 of the second extension rod 40 has the same structure and dimensions as that of the front combination portion 31 of the first extension rod 30, the plug 411 of the front combination portion 41 can be directly inserted into the insertion slot 231 of the rear combination portion 23, and the ball 421 of the elastic positioning member 42 on the plug 411 is elastically snapped and limited in the positioning hole 232 of the rear combination portion 23, so that the front combination portion 41 of the second extension rod 40 can be fixed in the rear combination portion 23 of the wrench body 20. After the second extension rod 40 is combined with the wrench body 20, the length of the three-piece wrench 10 is formed by the length L1 of the shaft 22 of the wrench body 20 combined with the length L3 of the second extension rod 40. In this way, the three-piece wrench 10 forms a third length (L1+L3), which can form a third operating arm of force and provide greater operating torsion.

Please refer to FIG. 7, which shows a fourth usage state of the three-piece wrench 10. To obtain a maximum usage length, firstly the front combination portion 31 of the first extension rod 30 is combined with the rear combination portion 23 of the wrench body 20, and then the front combination portion 41 of the second extension rod 40 and the rear combination portion 32 of the first extension rod 30 are combined together. Since the front combination portions 31, 41 and the rear combination portions 23, 32 can be combined with each other, the front combination portion 41 of the second extension rod 40 can be directly combined with the rear combination portion 32 of the first extension rod 30. Thereby, the length of the wrench 10 can be the longest, that is, a length (L1+L2+L3) formed by the shaft 22 of the wrench body 20 combined with the first extension rod 30 and the second extension rod 40. When using the wrench 10, the first extension rod 30 and the second extension rod 40 can be combined first, and then the front combination portion 31 of the first extension rod 30 is combined with the rear combination portion 23 of the wrench body 20.

In addition, when the wrench 10 is changed in length, the working head 21 of the wrench body 20 can be fixed on a workpiece (not shown in the figures) to perform the change directly without removing the wrench body 20 to increase the operating efficiency. After the three-piece wrench 10 is used, the first extension rod 30 and the second extension rod 40 can be directly combined to the rear end of the wrench body 20 and stored away as a whole to reduce required storage space and avoid the situation where the corresponding lengths cannot be found.

Please refer to FIG. 8, which is the three-piece wrench provided by a second preferred embodiment of the present invention. The structures of the first extension rod 30 and the second extension rod 40 are the same as that of the first embodiment, so they will not be described in detail, wherein:

the working head 21 and the shaft 22 of the wrench body 20 are separated parts, a rear end of the working head 21 is provided with a first connecting portion 211, which is a protrusion, and a front end of the shaft 22 being another end opposite to the rear combination portion 23 is disposed with a second connecting portion 221, which is two lugs; after the first connecting portion 211 and the second connecting portion 221 are connected with each other, a plug pin 24 passes through the first connecting portion 211 and the second connecting portion 221 to form a pivotal connection between the first connecting portion 211 and the second connecting portion 221, so that an operating angle between the working head 21 and the shaft 22 of the wrench body 20 can be adjusted to increase the variability of adjustment in an operating space.

Please refer to FIG. 9 for the three-piece wrench provided by a third preferred embodiment of the present invention, and the main structures are the same as that of the first embodiment, so they will not be described in detail, wherein:

the insertion slot 231 of the rear combination portion 23 of the wrench body 20 and the insertion slot 321 of the rear combination portion 32 of the first extension rod 30 are formed as square slots, and the plug 311 of the front combination portion 31 of the first extension rod 30 and the plug 411 of the front combination portion 41 of the second extension rod 40 are correspondingly formed as square cylinders, variation in shapes of the plug and the insertion slot is not limited, as long as the shapes are complementary and can be combined and fixed with each other.

Please refer to FIG. 10 for the three-piece wrench provided by a fourth preferred embodiment of the present invention, and the main structures are the same as that of the first embodiment, so they will not be described in detail, wherein:

in this preferred embodiment, since the length L2 of the first extension rod 30 and the length L3 of the second extension rod 40 are the same, the combined length (L1+L2) of the first extension rod 30 and the wrench body 20 is the same as the combined length (L1+L3) of the second extension rod 40 and the wrench body 20, in addition, the length L1 of the wrench body 20 is used alone, and the wrench body 20 is combined with the first extension rod 30 and the second extension rod 30 (L1+L2+L3), and thus the three-piece wrench 10 is capable of producing three different length variations, and users can arbitrarily choose to use the first extension rod 30 or the second extension rod 40 to combine with the wrench body 20 to obtain an equivalent moment of force.

The three-piece wrench provided by the present invention is capable of forming different length variations through combination of the different extension rods to produce different changes in length. Compared with the conventional wrench being a single tool with only one length, the present invention is capable of increasing the length applicability and variability of the wrench, producing various length variations by using only one wrench, also reducing the purchase costs and required storage space, reducing the weight of the wrench, and facilitating portability.

It is to be understood that the above description is only preferred embodiments of the present invention and is not used to limit the present invention, and changes in accordance with the concepts of the present invention may be made without departing from the spirit of the present invention, for example, the equivalent effects produced by various transformations, variations, modifications and applications made to the configurations or arrangements shall still fall within the scope covered by the appended claims of the present invention.

What is claimed is:

1. A three-piece wrench including:

a wrench body having a shaft and a working head, the working head being located at a front end of the shaft, the shaft having a length;

a first extension rod with a length;

a second extension rod with a length;

two rear combination portions respectively provided at rear ends of the shaft and the first extension rod, each said rear combination portion of the two rear combination portions has a same and uniform cross section extending a length thereof; and

two front combination portions respectively provided at front ends of the first extension rod and the second extension rod, each of the front combination portions and each of the rear combination portions being detachably combined;

the lengths of the first extension rod and the second extension rod being greater than the length of the shaft; and the wrench body, the first extension rod and the second extension rod providing variations in combination of various lengths of usage for the wrench;

wherein the length of the second extension rod is greater than the length of the first extension rod;

wherein each of the rear combination portions is respectively formed with an insertion slot, each of the front combination portions is respectively formed with a plug, and each of the plugs is capable of inserting into or detaching from each of the insertion slots.

2. The three-piece wrench as claimed in claim 1, further including two elastic positioning members respectively provided between each of the plugs and each of the insertion slots, when each of the plugs inserting into each of the insertion slots, the elastic positioning member keeping the plug in position.

3. The three-piece wrench as claimed in claim 2, wherein the two elastic positioning members are respectively composed of an elastic element and a ball, the two plugs are concavely provided with an accommodating hole respectively, so that each of the two elastic elements with each of the two balls can be respectively accommodated in one of the two accommodating holes, and peripheral walls of the two insertion slots are penetratively disposed with a positioning hole respectively.

4. The three-piece wrench as claimed in claim 1, wherein the insertion slot is a cylindrical slot, and the plug is a cylinder.

5. The three-piece wrench as claimed in claim 1, wherein the insertion slot is a polygonal slot, and the plug is a polygonal cylinder.

6. The three-piece wrench as claimed in claim 1, wherein the working head is integrally formed with the shaft.

7. The three-piece wrench as claimed in claim 1, wherein a rear end of the working head has a first connecting portion, the front end of the shaft has a second connecting portion, and a plug pin is pivotally connected with the first connecting portion and the second connecting portion overlap, so that the working head is capable of swinging relative to the shaft.

5

* * * * *